Primary Examiner — Elizabeth J Oswecki

CLAIM

The ornamental design for an earplug, as shown and described.

DESCRIPTION

FIG. 1 is a perspective view of an earplug showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a cross-sectional view taken along the line 9-9 shown in FIG. 7.

1 Claim, 9 Drawing Sheets
